(57) **CLAIM**

The ornamental design for an electroluminescence module, as shown and described.

DESCRIPTION

FIG. 1 is a front perspective view of a first embodiment electroluminescence module;

FIG. 2 is a rear perspective view thereof;

FIG. 3 is a front view thereof;

FIG. 4 is a left side view thereof;

FIG. 5 is a top plan view thereof;

FIG. 6 is a right side view thereof;

FIG. 7 is a rear view thereof;

FIG. 8 is a bottom plan view thereof;

FIG. 9 is a front perspective of a second embodiment thereof;

FIG. 10 is a rear perspective view thereof;

FIG. 11 is a front view thereof;

FIG. 12 is a left side view thereof;

FIG. 13 is a top plan view thereof;

FIG. 14 is a right side view thereof;

FIG. 15 is a rear view thereof; and,

FIG. 16 is a bottom plan view thereof.
